UNITED STATES PATENT OFFICE

118,963

DESIGN FOR A TUMBLER OR THE LIKE

William Lundy, Olean, N. Y., assignor to Olean Glass Company, Olean, N. Y., a corporation of
New York

Application June 8, 1939, Serial No. 85,406

Term of patent 14 years

To all whom it may concern:

Be it known that I, William Lundy, a citizen of the United States and residing at Olean, in the county of Cattaraugus and State of New York, have invented a new, original, and ornamental Design for a Tumbler or the like, of which the following is a specification, reference being had to the accompanying drawing, forming a part thereof, wherein:

Fig. 1 is an elevational view of a tumbler or the like embodying my new design;

Fig. 2 is a fragmentary longitudinal vertical section taken on line 2—2 of Fig. 1; and

Fig. 3 is a bottom plan view thereof.

I claim:

The ornamental design for a tumbler or the like, as shown.

WILLIAM LUNDY.
